FIG. 1 is a side elevational view of a disposable filter showing our new design;

FIG. 2 is a side elevational view looking from the left in FIG. 1;

FIG. 3 is a top plan view;

FIG. 4 is a plan view of the strainer illustrated in FIGS. 1 to 3 in a flat, open position; and

FIG. 5 is a cross-sectional, fragmentary view taken along the line 5—5 of FIG. 3.

The characteristic feature of our design resides in the combination on a conical filter of the particularly formed oppositely disposed apertures with the overlying mesh of

the particular form shown and the overlapping straight meeting line.

We claim:

The ornamental design for a disposable filter, substantially as shown and described.
